UNITED STATES PATENT OFFICE

102,957

DESIGN FOR A SHOVEL BLADE

Henry M. Renner, Elk City, Okla.

Application July 21, 1936, Serial No. 63,974

Term of patent 14 years

To all whom it may concern:

Be it known that I, Henry M. Renner, a citizen of the United States, residing at Elk City, in the county of Beckham and State of Oklahoma, have invented a new, original, and ornamental Design for a Shovel Blade, of which the following is a specification, reference being had to the accompanying drawing, forming part thereof.

Figure 1 is a perspective view of the shovel blade, showing my new design.

Figure 2 is a plan view, and

Figure 3 is a side elevation.

The characteristic feature of my design consists of a shallow and relatively broad concavo-convex shovel blade having parallel side edges merging into a convexly shaped serrated digging edge, the serration of the digging edge being cen-

trally located and substantially V-shaped, with the walls of the V convexly curved. Positioned within the forward part of the blade are a pair of parallel ribs of equal length, the forward ends of the ribs being well within the apices formed in the digging edge by the V-serration, and the apices being aligned with said ribs. The rear ends of the ribs terminate substantially centrally of the shovel blade. A handle socket projects centrally from the back edge of the blade at a sharp angle thereto, said back edge being substantially normal to the parallel side edges of the blade.

I claim:

The ornamental design for a shovel blade, as shown and described.

HENRY M. RENNER.
